UNITED STATES PATENT OFFICE.

JOHN B. MCKIBBIN, OF CRAFTON, PENNSYLVANIA, ASSIGNOR OF THREE-EIGHTHS TO EDMONDS J. SUGDEN, OF PITTSBURGH, PENNSYLVANIA.

SPIRAL REPEATING-GUIDE FOR ROLLING-MILLS.

1,178,252.

Specification of Letters Patent.

Patented Apr. 4, 1916.

Original application filed March 12, 1915, Serial No. 13,854. Divided and this application filed May 18, 1915. Serial No. 28,862.

To all whom it may concern:

Be it known that I, JOHN B. MCKIBBIN, a citizen of the United States, residing at Crafton, in the county of Allegheny and State of Pennsylvania, have invented certain new and useful Improvements in Spiral Repeating-Guides for Rolling-Mills, of which the following is a specification.

My invention relates to improvements in continuous rolling mills, utilizing a series of stands of reducing rolls, one of the rolls of each set being directly driven from a prime mover through continuously connecting journal couplings, in general axial alignment, and their co-acting rolls arranged either above or below said rolls, providing sets of three-high and two-high rolls, or with any other suitable arrangement of rolls, whereby to utilize the spiral repeating guide forming the subject matter of the present application. Said guide provides for the turning movement of the blank laterally toward the next pass, and for also reversing its direction, whereby to return it to the same or an adjacent stand of rolls, as hereinafter more fully described.

The present application is a division of my prior application for continuous rolling mills, filed March 12, 1915, Serial No. 13854. Referring to the drawings,—Figure 1 is a general plan view of the mill, portions being shown in section. Fig. 2 is a view of the several stands of rolls arranged in axial alignment, as viewed from the line II. II., Fig. 3 is a cross sectional view indicated by the line III. III. of Fig. 1.

Fig. 4 is a similar sectional view, indicated by the line IV. IV. of Fig. 1. Fig. 5 is a similar sectional view, indicated by the line V. V. of Fig. 1. Fig. 6 is a collective detail view, showing the two sides of the annular spiral guiding mechanism in internal and external elevation respectively. Fig. 7 is a detail vertical sectional view through a portion of the annular spiral guiding mechanism.

In describing the invention, and for the purpose of making its construction, operation and advantages entirely clear, it will be

described, and is illustrated, in connection with my improved continuous rolling mill, but, as stated, is not necessarily limited to such combination. In such mill, I provide a continuous series of rolls 2, 3, 4, 5, 6, in axial alignment, mounted in the usual housings of well-known construction, connected by the usual coupling boxes and spindles 8, 9, and adapted to be driven through coupling 10 from an engine or suitable driving motor. By this arrangement I utilize direct driving power throughout each of said several rolls, without the necessity of any intermediate gearing, thereby maintaining the power at a maximum with the highest efficiency and economy.

The first and second passes of the mill are provided between supplemental rolls 2, 2^a and 2^b, mounted in the housing directly above roll 2, and the third and fourth passes, between supplemental rolls 3, 3^a and 3^b, mounted directly above roll 3 in the housing, as shown, such supplemental rolls being connected by the usual boxes and spindles 8, 9, and driven through a train of gearing 11, whereby to transmit motion in the desired direction, and with a positive application of power, from the endmost spindle of the main axially connected train 2—3—4—5—6. Supplemental rolls 3^a and 3^b of the second stand are driven in the same way and direction, by intervening couplings, as will be readily understood.

The third stand of rolls consists of a main roll 4, and an upper roll 4^a idly mounted in the housing 7. The fourth stand consists of a main roll 5 and a lower roll 5^a mounted in the same way below the main roll; and the fifth stand consists of the main roll 6, and an upper idly mounted roll 6^a, the several rolls of each stand revolving in the direction indicated by the arrows. By this arrangement, it will be seen that in the first and second stands I provide three vertically arranged rolls, positively driven, the rolls of each stand operating alternately in opposite directions, and capable of acting on the blank in both directions, forward and back, the outermost of said rolls 2 and 2^b

respectively being capable of adjustment with relation to the center roll 2^a to accurately gage the pass in a manner well understood.

5 In the same manner the second stand of rolls, consisting of the main roll 3 and supplemental positively driven rolls 3^a and 3^b, is capable of simultaneously rolling the blank in both directions, the blank thereafter passing 10 through the single pass of the subsequent stands, to-wit, the third, fourth and fifth respectively, in alternating directions, the several idler rolls 4^a, 5^a and 6^a being caused to rotate and reduce the blank by 15 engagement therewith, and dependent on the driving action of the main rolls 4, 5 and 6.

As shown, the diameters of rolls 3, 5, 5 and 6 successively increase over the diameter of roll 2, whereby to increase their peripheries, so as to successively increase the peripheral speed of the rolls and the speed of the blank correspondingly, in conformity with its reduction by the successive 20 passes, and to take up the resulting increase in length of the blank, in conformity therewith. Thus, in practice, the diameter of roll 2 may be 12 inches; the diameter of roll 3, 13 inches; the diameter of roll 4, 14 25 inches; the diameter of roll 5, 16 inches; and the diameter of roll 6, 18 inches. By this arrangement I provide a straight line of directly driven rolls, each running at the same R. P. M. but each having an increased 30 peripheral speed successively throughout the series. The respective diameters of the rolls, however, may be, of course, varied or modified to suit the conditions of use, power, speed of the mill, or other circumstances within the province of the designing 35 engineer.

The first stand of rolls 2, 2^a, 2^b, is arranged with its passes in alinement with the discharge door of a furnace 12, from which 40 the blank 13 passes outwardly over feed rollers 14 positively driven by sprocket 45 gearing 15 or other suitable mechanism, by which the blank is delivered to the first pass between main roll 2 and roll 2^a.

50 Beyond the first pass of rolls, I arrange the spiral repeating guide 16, hereinafter described in detail, by means of which the blank is passed one or more times around within an outer shell and over an inner 55 drum, thereby being advanced spirally along and around said drum and within the shell, to a point where it emerges at the upper level in alinement with the second pass of the first stand of rolls, between rolls 60 2^a and 2^b. On the other side, beyond the first stand of rolls, and between it and the second stand, I provide guiding mechanism 65 whereby the blank is twisted up edgewise by means of a gradually varying guide face

on the inside of an abutment 17, which directs the blank around into the path between vertically arranged slightly tipped idler rollers 18 at the inside and 19, 19^a, at the outside thereof, between which the blank passes in a vertical position. One of said 70 rollers 19, 19^a, or both, may be so adjusted with relation to the roller 18 and the desired path of the blank, as to deflect it around and into engagement with the guiding abutment 20 to lead it to the reverse 75 pass. The blank then travels around in a reverse direction against an abutment 20, similar to abutment 17, having a gradually varying inner contacting face, by which the blank is turned over again flatwise and 80 guided into the third pass between the main roll 3 and supplemental roll 3^a of the second stand. Passing beyond said pass, it enters a second spiral repeating guide 16^a, similar 85 to guide 16, the convolutions whereof may be less, owing to the increased width of the blank and its lateral spacing. The blank then passes backwardly through the fourth pass, between roll 3^a and 3^b, and into a third spiral repeating guide 16^b, which may be of 90 increased length, whereby to advance the blank by several convolutions over to a position in alinement with the fifth pass, between rolls 4 and 4^a of the third stand. Beyond such pass I now provide a re-heating 95 or muffle furnace 21, of well-known construction, provided with fuel supply pipes 22, through the interior of which furnace, open at each end, the blank passes and emerges from the other end, being thus re-heated in transit. Beyond furnace 21, I provide a fourth spiral repeating guide 16^c, by which the blank is received at the upper level and spirally progressed around and along and delivered out therefrom at the 100 lower level, in alinement with the longitudinal chamber of a second re-heating furnace 21^a having similar fuel supply pipes 22^a. From said furnace the blank is introduced into the sixth pass, between rolls 5 and 5^a 110 of the fourth stand, beyond which it passes through a similar re-heating furnace 21^b having fuel supply pipes 22^b, and beyond such furnace is a fifth spiral repeating guide 16^d of the same kind as before described. 115 Said guide 16^d receives the blank at the lower level, advances it, and delivers it at the higher level, in a plane approximating that of the next roll pass. From such guide 16^d the blank emerges in alinement with 120 and passes through a fourth re-heating furnace 21^c having fuel supply pipes 22^c, and into the seventh pass between rolls 6 and 6^a, which are the finishing rolls.

It will be understood that the blank in its 125 passage beyond the several passes is supported by any suitable means, an idler rolls 23 or plates 24, of well-known construc-

tion. Also that, owing to the varying levels of the different passes, the furnaces 21 and 21^c may be on a higher level than furnaces 21^a and 21^b, which may be on a relatively 5 lower level, as clearly shown in Fig. 5.

Referring now to the spiral repeating guides 16, 16^a and 16^b, these consist, as shown in Fig. 6, of a two-part shell composed of semi-cylindrical portions 25, 25^a, 10 separably mounted to provide a continuous hollow drum, one of said sides, as 25, having on the entrance and exit side suitable inlet and outlet openings 25^b and 25^c, as will be readily understood.

15 A central winding drum 26 is mounted in suitable supports 27 and driven by a belt and pulley 28 or other suitable means in the proper direction.

The semi-cylindrical sides 25 are provided 20 with spiral inwardly projecting guides 29 throughout their interiors, so arranged as to form continuous spiral passages 30, the ends of the guides 29 being tapered or beveled, as indicated at 31, whereby to facilitate passage 25 of the end of the blank and prevent its sticking or binding at any point.

The construction of the several guides 16, 16^a and 16^b is generally similar, and that of 16^c and 16^d also, in respect of the 30 main inner winding drum 26^c and 26^d respectively, except that said drum is hollow, as indicated at 32, and is provided with hollow journals mounted in the supports 27^c and 27^d respectively. Through such hollow journals and the hollow center of each drum, I introduce a fuel supply pipe 33 having suitably spaced outlet apertures, by which gas may be introduced and burned within the drum for heating.

40 In connection with the spiral repeating guides 16, 16^a and 16^b, I also provide upper and lower supplemental rollers 34, 35, and in the case of guides 16^c and 16^d I provide upper and lower supplemental rollers 34^c, 35^c, and 34^d, 35^d, idly mounted in the supports 27^c and 27^d respectively, having hollow journals and each provided with a fuel supply pipe 36, of the same character and purpose as pipe 33. By this means the blank 45 in its passage around and through the spiral repeating guides is efficiently re-heated, in addition to the re-heating by the muffle furnaces 21, 21^a, 21^b, and 21^c. The result is that the blank is maintained in good condition 50 for rolling reduction throughout the several operations, and the continuous reduction is therefore effected without any undue strain on the rolls, thereby reducing the driving power to a minimum.

55 The advantages of the invention will be readily understood and appreciated by all those familiar with continuous rolling mill operations. It eliminates the necessity of any manual operation, requiring practically

no attention beyond the maintenance of the 65 parts in good operative condition.

The several reductions are effected successively and continuously throughout, the speed of operation may be accurately adjusted whereby to secure the best results with 70 a view to the work in hand, and it enables the accomplishment of rolling and finishing the blank directly from a slab or billet to any desired reduction as to finished shape and gage.

75 The blank in transit, as it is reduced to the smaller gages, is maintained in a ductile reducible condition by the supplemental re-heating treatments, which greatly add to the efficiency of the mill, while the directly 80 driven main rolls apply the power to the mill to the best advantage.

It will be understood that the mill is well adapted to the reduction of various sizes and shapes of material within its limitations 85 and possibilities as to the several manipulations provided for, but is best adapted to the rolling of flats. It greatly economizes the rolling of such shapes, while at the same time insuring uniformity as to gage and 90 character of the metal.

The invention may be variously changed or modified by the skilled mechanic or mill designer to suit the various contingencies of use, and I do not desire to be limited to the 95 particular arrangement, number of stands of rolls, or other parts, or the specific arrangement or detail construction of the elements, except as required by the scope of the allowed claims.

100 What I claim is:

1. In combination with reducing rolls, a spiral repeating guide having an outer cylindrical shell provided with inwardly directed spirally arranged guides, and an inner 105 actuating drum.

2. In combination with reducing rolls, a spiral repeating guide having an outer cylindrical shell provided with inwardly directed spirally arranged guides, an inner 110 actuating drum, and means for heating the said drum.

3. In combination with reducing rolls, a spiral repeating guide having an outer cylindrical shell provided with inwardly directed spirally arranged guides, an inner 115 actuating drum, and supplemental adjacent co-acting drums.

4. In combination with reducing rolls, a spiral repeating guide having an outer 120 cylindrical shell provided with inwardly directed spirally arranged guides, an inner actuating drum, and supplemental adjacent co-acting drums, said drums having hollow interiors and means for introducing fuel 125 thereinto.

5. Means for manipulating metal in the manner described consisting of a spiral re-

peating guide having an outer cylindrical shell provided with inwardly directed spirally arranged guides, and an inner rotatable actuating drum.

5 6. Means for manipulating metal in the manner described consisting of a spiral repeating guide having an outer cylindrical shell provided with inwardly directed spirally arranged guides, an inlet and an

outlet aperture, and an inner rotatable actuating drum.

In testimony whereof I hereunto affix my signature in the presence of two witnesses.

JOHN B. McKIBBEN.
